UNITED STATES PATENT OFFICE.

RICHARD FILTZ AND ALFRED LAKE, OF KINGSTON, ONTARIO, CANADA.

AUTOMATIC STOP-MOTION FOR KNITTING-MACHINES.

No. 890,038.

Specification of Letters Patent.

Patented June 9, 1908.

Application filed May 23, 1907. Serial No. 375,193.

To all whom it may concern:

Be it known that we, RICHARD FILTZ and ALFRED LAKE, subjects of the King of Great Britain, residing at the city of Kingston, county of Frontenac, in the Province of Ontario, Canada, have invented certain new and useful Improvements in Automatic Stop-Motions for Knitting-Machines; and we do hereby declare that the following is a full, clear, and exact description of the invention, such as will enable others skilled in the art to which it appertains to make and use the same.

This invention relates to knitting machines, and its object is to provide a new and improved stop motion, which is simple and durable in construction, very efficient and automatic in operation, and specifically designed to prevent large knots, imperfectly twisted yarn and bunches of loose material on the bobbins from passing into the knitting machine, thus overloading or choking up the needles and causing breakage of the latter, and other injury.

The invention further operates to stop the machine in case of breakage of the yarn, or through the end of the yarn on the bobbin having been reached.

The invention consists in the novel features of construction and relative arrangement of parts hereinafter fully described in the specification, clearly illustrated in the drawings, and particularly pointed out in the claims.

Referring to the accompanying drawings, forming a part of this application, and in which similar reference characters designate corresponding parts wherever they occur: Figure 1 is a view in elevation of one end of the knitting machine, showing the improvement applied thereto; Fig. 2 is a plan view of the same; Fig. 3 is a detail of the belt shipper taken on the line 3—3 of Fig. 1; Fig. 4 is an enlarged side elevation of the tripping mechanism; Fig. 5 is a front view of the same; Fig. 6 is a section on line 6—6 of Fig. 4, showing the stop motion slide as set for operation; Fig. 7 is a similar section showing the position of the parts after having been tripped to stop the machine; Fig. 8 is a section on line 8—8 of Fig. 7; Fig. 9 is a detail view of portions of the tripping mechanism, partly in section; Fig. 10 is a bottom view of the waste stripper, taken on the line 10—10 of Fig. 4; Fig. 11 is a side view of the waste stripper, showing by dotted lines the position

assumed when operating to stop the machine; Fig. 12 is a detailed view of the connections between the sections of the stop motion slide; Fig. 13 is an operating pin designed to be connected to the stop motion slide; Fig. 14 is a perspective view of the stop motion shaft; Fig. 15 is a perspective view of a connecting bracket; Fig. 16 is a side elevation of the automatic brake mechanism; Fig. 17 is a section of the same on line 17—17 of Fig. 16; and, Fig. 18 is a view of portions of the brake releasing mechanism.

The improved automatic stop motion is applied to a knitting machine of the ordinary or any preferred construction. As illustrated, it may comprise the bed or frame A, needle head B, needles C and thread feeding mechanism D. Power from any suitable source is applied to the main shaft E by means of the drive pulley F. An auxiliary shaft H drives the rotating mechanism by the beveled gears K. On the shaft H is arranged a fast pulley I and a loose pulley J, driven by a belt G passing over a pulley N on the shaft E. The thread or yarn M is led from the bobbin L through the improved stop device to the feed mechanism D.

Surrounding the bed or frame A, suitably supported in brackets, is the stop motion slide 1, designed when shifted laterally by the hereinafter described means, to ship the belt from the fast to the loose pulley, and simultaneously trip the brake mechanism to stop the machine. This slide consists of a narrow bar of suitable material extending along each side of the main bed or frame, and provided with suitable corner brackets 2, whereby lateral sliding motion of one section will be communicated to the other sections. These brackets comprise pins 3, mounted in the bracket frame, and slotted links 4 suitably held in any adjusted position on the pins 3. Connected with slides 1, adjacent the brackets 2, are the adjustable brackets 5, with depending pins 6^a engaging the links 4.

Lateral movement is given to the slide 1 by the trip mechanism (Figs. 4 to 9) constructed as follows. Suitably supported by the bed A is a depending bracket 6. Adjustably secured to the bracket 6 is a frame 7, provided with a pair of upwardly extending arms 8, suitably arranged for supporting the slide 1. Between these arms and the slide 1 is adjustably secured a block 9, having a depending lug 10, guided between a pair of guide rods 11 secured in the arms 8.

Below these guide rods, a rod 12, carrying a sliding collar 13 having an upwardly extending lug 14, is secured between the arms 8. This collar is normally spring-pressed to one end of the rod by means of the spiral spring 15 surrounding the rod, the collar and the depending lug 10 being of such dimensions that when the frame is moved by the spring it presses the lug 10, and consequently the slide 1 also, to one side. On the forward side of the collar is a lug 16, beveled on one side, and when the releasing mechanism is in the set position, as in Fig. 6, this lug is engaged by a weighted trigger 17, holding the device in the set position, *i. e.*, with the spring 15 under compression. The trigger is pivoted between upwardly extending lugs 18 on the frame 7. The weighted end of the trigger normally holds it in the position shown in Fig. 9, with the lug 19 thereof in position to engage the lug 16 on the collar. Extending forwardly from the pivot is the upturned arm 20, by means of which the trigger is tripped.

Secured in the frame 7, in proximity to the arm 20 of the trigger, is the vertical spindle 21, on which slides the flanged releasing weight 22, adapted when dropped, as shown in dotted lines, Fig. 4, to contact the arm 20 to trip the trigger. At the upper end of the spindle is a circular block 23, carrying the depending lever 24, pivoted thereto. A bent arm 25 on this lever is so arranged as to take under the flange of the weight and hold the same elevated (see Fig. 4). The lower end of the lever 24 is provided with an extension 26, arranged in the path of the arm 27 on the thread wire 28.

The thread wire 28 comprises the upwardly bowed member, terminating at its upper end in a thread engaging arm 29, and at its lower end in a block, by which it is pivoted in upwardly extending lugs on the frame, as at 30. The arrangement is such that when the thread wire is released from its full line position, Fig. 4, to the dotted line position, the lever arm 24 is moved, thereby releasing the weight 22.

An upwardly extending spindle 31, secured in the frame 7, supports at its upper end the adjustable blocks 32, carrying laterally extending thread-engaging arms 33, arranged with relation to the arm 29, one above and the other below. The spindle 31 also carries a platform 34, on which is supported the waste stripper 35. This waste stripper comprises a pair of parallel bars, 36, provided with teeth on their adjacent edges, and arranged apart a proper distance to allow the thread or yarn to pass freely therebetween, but to prevent tangles, knots, or loosely twisted portions from passing. These bars are supported by means of a depending yoke 37, pivoted in the rotating block 38, supported in the plate 34. 39 is a spring tending

normally to rotate the bars 36 to position parallel to the thread engaging arms 29 and 33. A lug 40 on the platform 34 normally prevents such rotation by engaging with the depending arm of the yoke 37, the yoke being, however, adapted, when moved about its pivot, to clear the said lug. Below the platform 34 on the spindle 31, is secured the thread eye 40a.

The thread or yarn M is led from the bobbin L through the guide eye 40a between the bars of the waste stripper, over the lower arm 33, is looped around the arm 29, and then passes under the upper arm 33 to the needle, it being understood that the mechanism above described is duplicated for each bobbin and thread.

In any convenient position on the bed A, is arranged a bracket 41, supporting the upright stop motion shaft 42, provided at its lower end with the slotted arm 43. Adjustably secured on the stop motion slide 1, in a convenient position, is the upwardly extending pin 44 (Fig. 13) arranged to engage the slot in the arm 43 to rock the shaft 42 when the slide is laterally displaced. Secured to the upper end of the shaft 42, and at a right angle to the arm 43, is an arm 45, at the end of which is pivoted a laterally swinging arm 46, slotted at its outer end. In a vertical bearing member 47, secured to a stationary portion of the machine, is a rock shaft 48, the upper end of which is connected by suitable links and levers to the slotted arm 46 to be rocked thereby. The lower end of the rock shaft carries a brake releasing pin 49, adapted, when the shaft is rocked, to release the long end of a bell lever 50, pivoted at 51 to a stationary portion of the mechanism. By means of the strong spring 52 acting through a series of levers 53 on the short arm 54 of the bell lever, the long arm is, as soon as released by the pin, pressed upwardly, engaging and elevating the arm 55 on the brake.

The brake consists of a suitably supported horizontal cylindrical casting 56, in which is mounted to slide the brake piston 57, provided within the casting at one end with the collar 58. A strong spring 59 surrounds the piston, bearing at one end against the collar 58, and at the other end against the removable plug 60, closing the end of the cylinder. The rear end of the piston carries a handle 61, and the forward end is provided with a brake shoe 62, provided with a thick rubber facing 63, suitably secured to the shoe, as shown in Fig. 17. Pivoted to the brake shoe is the arm 64, provided with the notch 65 in its under side, and carrying the arm 55 previously referred to. The lug 66 is provided on the cylinder support, so that when the piston is pulled back by the handle compressing the spring, the notch 65 engaging the lug 66 will hold the parts in set position. When forced forward, the brake shoe is 130

adapted to bear on a disk supporting the needle heads. A belt shipping mechanism is also provided, constructed as follows. Suitably journaled in a stationary portion of the mechanism, and in the main bed or frame, and extending below the same in proximity to the drive belt G, is a rotatable rod 67, provided at its lower end with a bent arm 68, arranged to engage the belt G and to ship the same from the fast pulley I to the loose pulley J when the rod 67 is rotated. The rod is rocked by a suitable lever 69 connected with the levers 53, as at 70, so as to be moved to one side under the influence of the spring 52, when the levers 53 are moved to release the brake.

The operation of our device is as follows: The thread or yarn being arranged as described, the brake is pulled back and set, the stop motion slide set as in Fig. 6, and the belt thrown to the fast pulley, whereupon the knitting proceeds uninterruptedly as long as the thread wire 28 is held in the full line position shown in Fig. 4. Should the thread be broken or be entirely unwound from the bobbin, the wire will be released, assuming the dotted line position shown in said figure. The same result is accomplished whenever knots, tangles, or flaws in the yarn reach the waste stripper, whereupon the stripper is pulled upward, rocking the yoke 37 so as to clear the pin 40, and thereby permitting the spring 39 to rotate the stripper so as to release the yarn from the arms 33 of the arm 29. The dropping of the thread wire 28 tilts the lever 24 through the contact of the arms 27 and 26, thus releasing the weight 22, which immediately drops on to the upwardly extending arm 20 of the trigger, thus tilting the same so as to release the collar 13 and allow it, together with the slide 1, to be shifted laterally by means of the spring 15. This lateral movement acting through the shaft 42 and its connections, rocks the shaft 48, thus releasing the bell lever arm 51 and allowing it to be thrown upward under the influence of the spring 52. The arm 51, through contact with the arm 55, on the brake, releases the notch 65 from its engagement with the lug 66, thus permitting the spring 59 to act to set the brake. Simultaneously with this action, the lever 69 is shifted, and through the shaft 67 and arm 68, the belt is shipped to the loose pulley.

It will thus be seen that a positively acting device is obtained, which is entirely automatic in action, and which will detect any flaw in time to prevent damage to the material knitted, or to the machine. In addition to the great saving in value of the finished product and in the cost of maintenance and repairs to the machine, through being entirely automatic, it enables one operator to attend to a number of machines, thus effecting a substantial saving in the cost of labor.

It is to be understood that the stop motion device may be applied to other forms of knitting machines than the one described, and the device is in itself adapted to many changes in arrangement and construction without departing from the spirit of the invention as defined in the appended claims.

Having thus fully described our invention, what we claim as new, and desire to secure by Letters Patent, is:

1. In a stop motion for knitting machines, a laterally movable slide, a spring for operating said slide, a pivoted trigger, and means coöperating therewith for holding said spring compressed in position to operate said slide, a vertically sliding weight in proximity to said trigger, a lever having an arm engaging said weight and holding the same in its raised position, a pivoted thread wire held in raised position by the knitting thread, an arm on said wire arranged when said wire is released to contact said weight supporting lever to release said weight whereby said trigger is tripped, and devices controlled by said slide for stopping the knitting machine. 75
2. In a stop motion for knitting machines, a laterally movable slide, a spring for operating said slide, a pivoted trigger and means coöperating therewith for holding said spring compressed in position to operate said slide, a pivoted thread wire held in raised position by the knitting thread, connections between said wire and said trigger whereby when said wire is released said trigger is tripped, a waste stripper through which said thread passes, means for rotating said stripper when pressure is applied thereto, whereby said thread is released from said thread wire, and devices controlled by said slide for stopping the knitting machine. 90
3. In a stop motion for knitting machines, a laterally movable slide, a spring for operating said slide, a pivoted trigger, and means coöperating therewith for holding said spring compressed in position to operate said slide, a vertically sliding weight in proximity to said trigger, a lever having an arm engaging said weight and holding the same in its raised position, a pivoted thread wire held in raised position by the knitting thread, an arm on said wire arranged when said wire is released to contact said weight supporting lever to release said weight whereby said trigger is tripped, a waste stripper through which said thread passes, means for rotating said stripper when pressure is applied thereto, whereby said thread is released from said thread wire, and devices controlled by said slide for stopping the knitting machine. 100
4. In a stop motion for knitting machines, in combination with a belt shipper and a brake, a pivoted thread wire controlling the same held in raised position by the knitting thread, and a waste stripper through which said thread passes, and means for rotating 115
5. In a stop motion for knitting machines, in combination with a belt shipper and a brake, a pivoted thread wire controlling the same held in raised position by the knitting thread, and a waste stripper through which said thread passes, means for rotating said stripper when pressure is applied thereto, whereby said thread is released from said thread wire, and devices controlled by said slide for stopping the knitting machine. 120
6. In a stop motion for knitting machines, in combination with a belt shipper and a brake, a pivoted thread wire controlling the same held in raised position by the knitting thread, and a waste stripper through which said thread passes, and means for rotating 130

4
said stripper when pressure is applied thereto, whereby said thread is released from said thread wire.

5. In a stop motion for knitting machines, in combination with a belt shipper and a brake, a pivoted thread wire controlling the same held in raised position by the knitting thread, and a rockable and rotatable waste stripper through which said thread passes, a 10 spring normally tending to rotate said stripper, and means preventing such rotation but arranged when pressure is applied to said stripper to permit rotation thereof, whereby the knitting thread is released from engagement with the thread wire.

6. In a stop motion for knitting machines, a laterally movable slide, a spring for operating said slide, a pivoted trigger, and means coöperating therewith for holding said spring 20 compressed in position to operate said slide, a vertically sliding weight in proximity to said trigger, a lever having an arm engaging said weight and holding the same in its raised position, a pivoted-thread wire held in raised 25 position by the knitting thread, an arm on said wire arranged when said wire is released to contact said weight supporting lever to release said weight whereby said trigger is tripped, a rockable and rotatable waste stripper through which said thread passes, a spring 30 normally tending to rotate said stripper, and means preventing such rotation arranged when pressure is applied to said stripper to permit rotation thereof whereby the knitting 35 thread is released from engagement with the thread wire, and devices controlled by said slide for stopping the knitting machine.

7. In a stop motion for knitting machines, a laterally movable slide, a spring for operating said slide, a pivoted trigger and means coöperating therewith for holding said spring compressed in position to operate said slide, a suspended weight above said trigger, means 40 controlled by the knitting thread for releasing said weight whereby said trigger is tripped, a spring operated brake, spring operated releasing means for said brake, a rock shaft controlling said releasing means and connections to said slide whereby when said 45 slide is moved said brake is allowed to set, and a belt shipper connected to said releasing means and operated thereby.

8. In a stop motion for knitting machines, a laterally movable slide, a spring for operating said slide, a pivoted trigger and means coöperating therewith for holding said spring compressed in position to operate said slide, a suspended weight above said trigger, a pivoted thread wire held in raised position 50 by the knitting thread, connections between said wire and the weight for releasing said weight when the wire is released through breakage or exhaustion of the thread whereby said trigger is tripped, a spring-operated 55 brake, spring-operated releasing means for

said brake, a rock shaft controlling said releasing means and connections to said slide whereby when said slide is moved said brake is allowed to set, and a belt shipper connected to said releasing means and operated 70 thereby.

9. In a stop motion for knitting machines, a laterally movable slide, a spring for operating said slide, a pivoted trigger and means coöperating therewith for holding said spring 75 compressed in position to operate said slide, a suspended weight above said trigger, means controlled by the knitting thread for releasing said weight whereby said trigger is tripped, a waste stripper through which said 80 thread passes, means for rotating said stripper when pressure is applied thereto whereby said thread is released from said controlling means, a spring-operated brake, releasing means for said brake, a rock shaft controlling 85 said releasing means and connected to said slide whereby when said slide is moved said brake is allowed to set, and a belt shipper connected to said releasing means and operated thereby.

10. In a stop motion for knitting machines, a laterally movable slide, a spring for operating said slide, a pivoted trigger and means coöperating therewith for holding said spring 90 compressed in position to operate said slide, a suspended weight above said trigger, means controlled by the knitting thread for releasing said weight whereby said trigger is tripped, a rock shaft operated by said slide, a spring-operated lever, and a second rock shaft operated thereby, a belt shipper operated by said second rock shaft, connections between said first-mentioned rock shaft and said spring-operated lever, whereby when said shaft is rocked said lever is released to be operated, and a spring-operated 100 brake also controlled by said first-mentioned rock shaft.

In a stop motion for knitting machines, laterally movable slide, a spring for 110 operating said slide, a pivoted trigger and means coöperating therewith for holding said spring compressed in position to operate said slide, a suspended weight above said trigger, a pivoted thread wire held in raised 115 position by the knitting thread, connections between said wire and the weight for releasing said weight when the wire is released through breakage or exhaustion of the thread whereby said trigger is tripped, a rock shaft 120 operated by said slide, a spring-operated lever, and a second rock shaft operated thereby, a belt shipper operated by said second rock shaft, connections between said first-mentioned rock shaft and said spring-operated 125 lever, whereby when said shaft is rocked said lever is released to be operated, and a spring-operated brake also controlled by said first-mentioned rock shaft.

12. In a stop motion for knitting ma- 130

chines, a laterally movable slide, a spring for operating said slide, a pivoted trigger, and means coöoperating therewith for holding said spring compressed in position to operate said slide, a vertically sliding weight in proximity to said trigger, a lever having an arm engaging said weight and holding the same in its raised position, a pivoted thread wire held in raised position by the knitting thread, an arm on said wire arranged when said wire is released to contact said weight supporting lever to release said weight whereby said trigger is tripped, a waste stripper through which said thread passes, means for rotating said stripper when pressure is applied thereto, whereby said thread is released from said thread wire, a rock shaft operated by said

slide, a spring-operated lever, and a second rock shaft operated thereby, a belt shipper operated by said second rock shaft, connections between said first-mentioned rock shaft and said spring-operated lever, whereby when said shaft is rocked said lever is released to be operated, and a spring-operated brake also controlled by said first-mentioned rock shaft. 20

In witness whereof we have hereunto set our hands in the presence of two witnesses.

RICHARD FILTZ.
ALFRED LAKE.
